CINDER POT

Archibald D. Davies, Pittsburgh, Pa.

Application May 14, 1938, Serial No. 207,987

4 Claims. (Cl. 266—39)

This invention relates to pots for handling molten slag, cinder and the like from blast and open hearth furnaces, and more particularly to a cinder pot having a flexible side wall of irregular shape in cross section.

Cinder pots having a side wall of irregular shape in cross section have been made heretofore but in all such pots, known to me, the side wall was of substantially the shape of a sinusoid 5 curve in section and of uniform thickness from the top to the bottom of the pot to provide what may be termed "longitudinal corrugations". These corrugations formed, in effect, a side wall made up of a series of alternate peaks and valleys. It has been found that where such corrugated pots are in use and filled with molten slag the valleys become visibly hot and are of a substantially cherry or dull red color in appearance, while the peaks remain substantially grey in 10 color, and I believe that this is due to the fact that the area of the heat absorbing surfaces opposite the valleys is greater than the area of the heat radiating surfaces of the valleys on the outside of the pot, while at the peaks the reverse 15 is true since the heat radiating surfaces of the peaks are considerably greater than the heat absorbing surfaces on the inside of the pot and opposite such peaks.

Inspection of the corrugated pots now in service discloses that the intense heat to which the pots are subjected, and especially that portion opposite the valleys of such pots, tends to cause the metal to disintegrate and, as a result, fire cracks, which reduce the life of the pot, invariably occur along the ridges on the inside of the pot directly opposite the valleys in the outer surface thereof.

One object of the present invention is to provide a cinder pot having a side wall of irregular shape in section in which the area of the heat absorbing surfaces at any point in the side wall is substantially equal to the heat radiating surfaces at that point, and I accomplish this object by providing a side wall having a series of substantially channel-shaped sections therein, which taper both in width and depth from the rim toward the bottom of the pot.

Another object of this invention is to provide a cinder pot having a side wall provided with a series of channel sections of substantially channel-shape and in which the legs of the channel sections are substantially radially disposed and act as stiffening ribs or beams for the side wall of the pot.

55 A further object is to provide a cinder pot

having a flexible side wall free to expand and contract, which is of varied thickness, the greatest thickness being at or near that portion of the wall which is subject to the greatest heat when the pot is in use to thereby reduce disintegration of the metal due to fire cracking and thereby increase the life of the pot.

These and other objects which will hereinafter be made apparent to those skilled in this particular art are accomplished by means of this invention, one embodiment of which is described in the following specification and illustrated in the accompanying drawing, in which:

Figure 1 is a top plan view of a pot made in accordance with my invention; 15

Fig. 2 is a sectional view taken on the line II—II of Fig. 1;

Fig. 3 is a view in side elevation of the pot;

Fig. 4 is an enlarged detail view illustrating the construction of the side wall; 20

Fig. 5 is a partial plan view of another exemplification of my invention; and

Fig. 6 is a sectional view taken on the line VIII—VIII of Fig. 5.

In Figs. 1 and 4 of the drawing, a cinder pot 10 is shown having a bottom 11 of substantially spheroidal shape and a side wall 12 extending upwardly and outwardly from the bottom 11, which is made in accordance with my invention and designed to withstand bulging and disintegration of the metal due to fire cracking. The side wall 12 is made up of a series of circumferentially spaced substantially channel-shaped sections 13 which extend from the rim to the bottom of the pot, with the legs 14 of the channel sections 13 extending outwardly and connected together at their outer ends by wall portions 15. The channel sections 13 taper both in width and depth from the top toward the bottom of the pot 10 and the legs 14, which act as stiffening beams or ribs for the pot, extend beyond the tangent point between the side wall and the spheroidal bottom 11 and merge with the bottom 11 at a point beyond such tangent point, to increase the flexibility of the spheroidal bottom to 30 better resist the strains of expansion and contraction. The ribs 14 are substantially radial of the pot and the surfaces thereof, which are inside the pot, are flared outwardly and filleted to the inner portions of the surfaces 15 of the side 35 walls, so as to provide recesses 16 between the channel sections which are somewhat wider at their mouth than they are at the bottom.

With this construction, it is apparent that pots made in accordance with my invention, may be 45

readily emptied although the slag or cinder cast therein has solidified and a shell has been formed adjacent the inner surface of the pot, of the same shape in section as the inner surface of the pot, because in my construction the recesses or spaces between adjacent channel sections are wider at their mouth than at the bottom thereof and, consequently, binding of the shell within the pot is eliminated.

10 A pot constructed as herein described is flexible from the standpoint of thermal expansion and contraction for the reason that the bottom being spheroidal in shape embodies the thermo-expansive flexible properties of a sphere and the channel sections 13 permit the wall of the pot to freely expand and contract circumferentially with changes in temperature.

15 Since the channel sections increase both in depth and width from the bottom to the rim of the pot, the actual circumferential length of the wall section at successive horizontal elevations increases at successively greater rates than the change in diameter and, as a result, the pot will not develop bulges and cracks as a result of repeated and severe temperature changes.

20 It should be noted that in a pot constructed in accordance with my invention and having substantially channel-shaped sections therein, the heat radiating surfaces of the pot are substantially equal to the heat absorbing surfaces thereof. That is to say, the space A between the channel sections 13 on the inside of the pot, which absorbs the heat from the molten slag poured therein is somewhat less than the area of the heat radiating portion A' of the surface 15 on the outside of the pot; the area of the heat absorbing surface of the base of the channel section marked "B" is somewhat less than the area of the heat radiating surface B' on the outside of the pot, and the area of the heat absorbing surfaces C of the legs 14 on the inside of the pot is substantially equal to the area of heat radiating surfaces C' of the legs 14 on the outside of the pot. Consequently, the heat absorbing surfaces of the pot are all substantially equal to but not greater than the heat radiating surfaces thereof and the strains ordinarily set up in a pot as a result of uneven heating of the various sections thereof are eliminated in a pot made in accordance with my invention.

25 50 In order to prevent disintegration of the metal in the side wall 12, due to fire cracking and the like, the wall 12 is of varying thickness and increases in thickness from the bottom to a point 17 adjacent or slightly above the trunnion ring, which actual tests show to be the hottest part of the pot, and then decreases from that point to the original thickness at the rim of the pot, and I prefer that the wall at the point 17 be approximately 40% thicker than the thickness of the wall at the bottom and rim portions thereof.

30 55 From the foregoing description, it is apparent that the legs 14 of the channel-shaped channel sections 13 of my improved pot act as stiffening beams or ribs and, consequently, my pot is of substantially greater strength than a wall of any other shape having the same weight or thickness.

50 65 The pot 10 is of the type designed and primarily used for slag cars and buggies, and for this purpose support pads or lugs are spaced uniformly around the pot and located at or slightly above the middle thereof for supporting the pot on the trunnion ring of a car or buggy (none shown) in the usual manner. The support pads, 70 75 which comprise a horizontal section 18 apertured

to receive a supporting bolt and two vertical rib portions 19, are formed on the surfaces 15 between the channel sections 13 and not only strengthen this portion of the pot but also facilitate the casting of the pot.

5

10 When a pot of the character herein described is in use, it frequently happens that the molten slag is permitted to solidify therein before the pot is emptied. As the slag solidifies, a shell is formed around the inside surface of the pot 10 which becomes thicker and thicker as the cooling increases, and with my pot, since the inner surfaces of the ribs are spaced wider at the mouth of the recesses than at the inner portion, this shell may be readily removed without binding 15 within the recesses.

15 Figs. 5 and 6 illustrate another exemplification of my invention in which the side wall 12b of the pot is provided with circumferentially spaced inwardly projecting channel sections 13b. In this exemplification, however, the thickness of the side walls varies both circumferentially and longitudinally i. e., the base portions of the sections are of substantially greater thickness than the remaining portions of the side wall, to increase 20 the side wall thickness at the hottest points of the pot and to decrease disintegration of the metal due to fire cracking and, consequently, increase the life of the pot. In this modification, the base 13c of each channel section 13b is 25 thickest at the upper end thereof and decreases in thickness from the top of the pot to the bottom where they are of the same thickness as the remainder of the side wall.

30 35 From the foregoing description of my invention, it is apparent that I have produced a cinder pot having a flexible side wall in which the heat absorption area is somewhat less than (never greater than) the area of the heat radiating surface and that, as a result, all parts of the pot are 40 subjected when in use to the same conditions and disintegration of the pot, due to localized temperature strains, is thereby eliminated.

45 It is further apparent that the shape of the channel sections of my improved pot gives a stronger side wall than a corrugated wall of the same weight and thickness, and that my improved wall design is much stronger than the ordinary uncorrugated or circular pots now in general use.

50 55 While I have described one embodiment of my invention, it is to be understood that certain changes, additions, subtractions and omissions may be made therein without departing from the spirit of my invention or the scope of the appended claims.

Having thus described my invention, what I claim as new and desire to secure by Letters Patent is:

1. A cinder pot for receiving molten slag and the like having a closed spheroidal bottom and an upwardly diverging side wall, the said side wall being of increased thickness intermediate its top and bottom and being provided with a series of circumferentially spaced tapered substantially flat-bottomed channel-shaped sections provided with legs connecting adjacent sections together.

2. A cinder pot for receiving molten slag and the like having a closed spheroidal bottom and an upwardly diverging side wall, the said side wall increasing gradually in thickness from a point adjacent the bottom to a point corresponding substantially to that portion of the pot which becomes hottest and thereafter decreasing grad-

ually in thickness to the rim of the pot and being provided with a series of circumferentially spaced tapered substantially flat-bottomed channel-shaped sections terminating below the point of tangency between said wall and said bottom, legs being provided to connect adjacent sections together.

3. A cinder pot for receiving molten slag and the like having a closed spheroidal bottom and an upwardly diverging side wall, the said side wall being of increased thickness intermediate its top and bottom and being provided with a series of circumferentially spaced tapered substantially flat-bottomed channel-shaped sections provided with legs connecting adjacent sections together,

each such section having a heat absorbing surface and a heat radiating surface the former of which is not greater than the latter.

4. A cinder pot for receiving molten slag and the like having a closed spheroidal bottom and an upwardly diverging side wall, the said side wall being of increased thickness intermediate its top and bottom and being provided with a series of circumferentially spaced tapered substantially flat-bottomed channel-shaped sections provided with legs connecting adjacent sections together, the construction and arrangement being such that the said side wall alternately increases and decreases in thickness circumferentially.
